CLAIM

The ornamental design for a cosmetic carrying case, as shown and described.

DESCRIPTION

FIG. 1 is a front perspective view of the cosmetic carrying case.

FIG. 2 is a front open view of the cosmetic carrying case.

FIG. 3 is a back open view of the cosmetic carrying case.

FIG. 4 is a left open view of the cosmetic carrying case.

FIG. 5 is a right open view of the cosmetic carrying case.

FIG. 6 is a top open view of the cosmetic carrying case; and,

FIG. 7 is a bottom open view of the cosmetic carrying case.

The broken lines immediately adjacent the shaded areas represent the bounds of the claim and all other broken lines are for illustrative purposes only. None of the broken lines form a part of the claimed design.
